UNITED STATES PATENT OFFICE

126,300

DESIGN FOR A DRESS

Murray Marve, New York, N. Y.

Application February 4, 1941, Serial No. 98,718

Term of patent 3½ years

To all whom it may concern:

Be it known that I, Murray Marve, a citizen of the United States, residing in New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

MURRAY MARVE.
